WEARING APPAREL

Hyatt Lemoine, Maywood, N. J.

Application June 16, 1934, Serial No. 731,006

9 Claims. (CL. 2—70)

The present invention relates to wearing apparel and has particular application to slide fastener constructions which may be applied in combination garments, such as overalls or children's garments.

In the usual types of garments or closures employing slide fasteners, the amount of opening or attachment which could be secured by the slide fastener was necessarily limited. To secure complete closure it was necessary to employ a plurality of slide fastenings or to combine such slide fasteners with other types of fasteners such as buttons, snap fasteners and so forth.

Due to the difficulty that slide fasteners would only permit limited opening of the garments, and also due to the fact that large portions of the garments had to be closed by the old type of fasteners, buttons, hooks and eyes or snap fasteners, the use of slide fasteners in garments has been somewhat limited.

These difficulties have been particularly apparent in combination overall garments, where both the opening in the front of the trousers and of the shirt had to be closed by other means than slide fasteners and the slide fastener could only be utilized to enable partial opening of the garment between the jacket portion and trouser portion.

An object of the present invention is to provide an improved garment of simple and practical construction in which the jacket and trouser sections thereof are connected in such a manner as to constitute in effect a one-piece garment and wherein said sections may be readily and quickly joined together and detached from one another by the use of a simple fastening construction, which, if desired, also may be used for closing the normal front openings in both the jacket and trousers.

Another object is to provide an overall garment, the jacket and trousers sections of which are provided with a separable fastener mechanism, or a slide fastener construction, which will enable ready closing of the front of the jacket, of the fly of the trousers, and ready connections between the trouser and jacket sections, preferably by the manipulation of a single sliding fastener element, which nevertheless will permit ready opening of the various portions of the garments during usage.

Another object is to provide an improved slide or fastener construction or mechanism which lends itself to the utilization of a single sliding fastener element to close the various sections of wearing apparel or other closures.

In the preferred embodiment of the present invention an overall construction will be utilized

to illustrate the application of the invention, and in this overall construction the slide fasteners are connected along the front opening of the jacket member, the fly opening of the trouser section and along the waistline of the jacket and trousers elements.

The fastener is preferably of the type which permits total separation between the jacket and the blouse element and also complete separation at the front of the jacket.

In the preferred construction, the slide fastener slider is started at the top of the front closure of the jacket and then is continued down to the bottom of the jacket to close the jacket. Then it is turned to the connection between the jacket and the trousers and is run around the waist. Then after it has completed the connection between the jacket and trousers, it is run down the fly opening to close the same.

During usage the fly may be opened by pulling up on the slide fastener, or both the fly may be opened and the trousers detached from the jacket by pulling the slide fastener over the fly and then around the waist.

The opposing cooperating teeth of the slide fastener are preferably provided with initial connection means by which the two strips may be connected together to permit movement of the slide thereupon to cause engagement of the teeth.

At the end of the strip at the front of the waist and at the end of the strip of the slide fastener elements around the waist, a guide means is preferably provided for enabling the slide fastener or sliding member to be moved off one fastener element and to be started on another fastener element.

A snap fastening means is also preferably provided to lock the ends of the slide fastening strips from which the sliding cam members have been removed, such as at the bottom of the jacket and the end of the connection of the jacket and trousers sections.

The above and other objects will appear more clearly from the following detailed description, when taken in connection with the accompanying drawings, which illustrate a preferred embodiment of the inventive idea.

In the drawings:

Figures 1 to 4 show one embodiment of the present invention in which the slide fastener is applied to the connection of the trousers and jacket elements of an overall combination, Fig. 1 being a front elevation of the garment showing the parts assembled, Fig. 2 being a similar view illustrating the parts detached from one another, 55

Fig. 3 being an enlarged fragmentary elevation with the cover flaps of the separable connection illustrated to show portions of the latter, and Fig. 4 being a vertical sectional view substantially 5 upon the line 4—4 of Fig. 1.

Figures 5 to 7 show another embodiment of the invention, to which the present application is particularly directed, Fig. 5 being a front elevational view of the combined garment showing the 10 parts assembled similar to Fig. 1, and Figs. 6 and 7 being enlarged detail views showing the slide fastener construction.

The construction just described is set forth in my prior filed abandoned application Serial No. 15 423,575, filed January 27th, 1930.

Figures 1 to 4 of the present application correspond to Figures 1 to 4 of said prior abandoned application.

In Figs. 5 to 7 is shown a different embodiment 20 in which the front of the jacket section, the fly of the trousers section, as well as the connection between the jacket and trousers section are connected by a single sliding cam fastener which may first be passed down over the front of the blouse 25 or jacket to close the same, then around the waist to connect the garment sections and then down the fly to close the trousers.

In Figs. 5 to 7 parts functioning similarly as 30 in Figs. 1 to 4 will be indicated by the same numerals primed.

In Figs. 5 and 6 the slide fasteners are not only provided around the waist, as indicated by the numerals 9', 10', 11' but they also are provided as indicated at 20 and 21 along the front 35 of the jacket at 20 and along the fly of the trousers at 21.

The present garment is primarily designed to overcome certain difficulties and disadvantages existent in known one-piece overalls, such as the 40 inability to remove or lower the trouser section without first unfastening the shirt section and disengaging the arms from the sleeves thereof. At the same time, the instant garment, by having the sections separably connected and assembled 45 in the manner to later appear, has all of the inherent advantages of a one-piece garment in addition to the fact that either section may be used by itself, if so desired.

By reference to the accompanying drawings, 50 it will be seen that the garment comprises the trouser and shirt sections 5 and 6, respectively, which may be made of any suitable material and formed with pockets in the usual manner, the trouser section also having loops 7 about the 55 waistline for receiving a belt when said section is used to the exclusion of section 6. The trouser section, in addition to the usual button fastenings, may also have a snap fastener 8 at the upper end of the fly portion.

The upper edge of the section 5 has stitched or otherwise fastened thereto a strip 9, which in the form shown, extends entirely about the waist portion.

The edge of said strip which projects above the 65 end of the trouser section carries the elements 10 of a separable fastener mechanism of well-known construction and said elements cooperate with similar ones carried by a strip 11 attached to the interior of the section 6 above the bottom edge 70 thereof to secure the latter to the section 5 when the entire garment is being employed.

The separable fastener mechanism further includes the slide 12 which is permanently connected to one of the series of elements 10, those 75 carried by the strip 9, for instance, and is adapted

to receive the other series of elements 10 on the strip 11 and cause said series to be interengaged as the slide is moved from the left-hand end of the fastener, as shown in Figure 2, to its fully operated position at the right of Figure 3.

To attain the latter position, the slide moves completely around the waist and in so doing the elements 10 attached to the shirt section pass through the slide and are thus interengaged with the elements 10 carried by the strip 9.

With the sections of the garment thus connected, the same combine to form the equivalent of a one-piece overall.

In order to completely detach the two sections 5 and 6, the slide 12 is moved in a reverse direction from that above described until the series of elements 10 carried by the strip 11 are entirely disconnected from the slide which latter still remains attached to the series of elements secured to the strip 9.

The sections 5 and 6 are now completely detached one from the other.

In order that the elements 10 of the separable fastener may be prevented from coming in contact with the body or undergarment of the wearer, the section 6 has secured to the inner surface thereof a flap 13 which covers said elements.

This flap is preferably secured in place by the same means which is utilized to attach the strip 11 to the section 6 and from this point of attachment downwardly the remainder of the shirt section constitutes an outer covering flap 14 extending around the shirt and of sufficient width to extend over the elements 10 and also cover the snap fastener 8, thereby imparting to the undergarment a neat and attractive appearance.

Preferably a single slider or cam member 12' is provided for these fasteners 10', 20 and 21, and this slide fastener is started at 23 adjacent the neck of the wearer to close the jacket, as indicated by the arrow 25.

It is then continued around the waist, as indicated by the arrows 25 and 26. After having completed connection along the waist between the jacket 6' and the trousers 5' it is continued 45 down to close the fly as indicated by the arrow 27.

The reverse operation of first opening the fly is indicated by the dotted arrow 28. When it is desired to detach the jacket from the trousers, 50 the slider 12' is then moved from the top of the fastener 21 around the waist, as indicated by the arrows 28 and 29.

Finally, when it is desired to open the jacket the slider is pulled up along the front of the 55 jacket, as indicated by the arrow 30.

The jacket shown in Fig. 5 is provided with detachable connections at 23, 32 and 33 enabling initiation of the cam slider along the slide fasteners 10', 20 and 21, respectively.

These connections to enable initiation of the sliding cam member are shown in detail in Fig. 6 at the points 32 and 33, 32 showing the connection after it has been made and 33 showing the connection in the process of being made.

In Fig. 6, after the slider 12' is pulled off the waist slide fastener 10', it passes around the hollow guiding member 34 and then onto the beaded edge 35.

The slide fastener 21 is provided with the opposite cooperating teeth 36 and 37.

It will be noted that the channel of the slider 12' indicated by the dimension arrows 38 in Fig. 6 is of sufficient magnitude to enable the slider 71

12' to pass over and be guided by the quarter-circular guide member 34.

When the slider member is in the position indicated at 33, the nose 39 projecting from the 5 end of the row of the teeth 36 of the slide fastener 21 may be inserted into the other side of the slide 12' indicated at 40 until the flat oblique end 41 of the nose contacts with the end of the guide.

10 Connected to the inside of the nose 41 is the hook 42 which will then be ready to pass into the opening 43 in the end of the quarter-circular guide 34 upon further movement of the slider 12' to interlock the teeth 36 and 37 when the 15 slider is pulled down to close the slide fastener 21 along the fly of the trousers 5.

The initial connection, after being formed, is best shown at 32 and similarly functioning parts are indicated by the same numerals at 32. At 20 32, the initial end of the slide fastener is securely locked by the hook 42 engaging the end of the guide 34, after the slider has passed thereover, following the engagement as indicated at 33. A similar device as shown at 32 and 33 may be used 25 at 23 in Fig. 5.

To lock the slide-off ends of the slide fasteners when the slider cam has passed therefrom, these ends being indicated at 44 and 45 in Fig. 5, it is desirable both to provide fullness in the garment 30 as indicated at 46, 47 and 48 in Fig. 5 to prevent as far as possible stresses being applied to the slide-off ends of the hookless fasteners. In addition, locking means are preferably provided, as indicated at 49 and 50, in Fig. 6.

35 The locking means 49 of Fig. 6 is shown in larger scale in Fig. 7, and it is automatically opened and closed by the movement of the slider cam member 12'. The locking device 50 is automatically closed, but must be opened to detach 40 the jacket 6' from the trousers 5' and to enable the slide fastener to be placed upon the row 10' in its movement 28-29.

Referring to Figs. 6 and 7, the end tooth 51 of the slide fastener row 20 at the front of the 45 jacket is provided with a double projection 52 instead of the single projection of the remaining teeth. Engaging with the tooth 52 are two closely spaced opposite teeth 53 on the opposite tape which are provided with inwardly facing recesses 54. It will be noted that the lower faces of these 50 teeth 53 abut, as indicated at 55, and that they are connected to the bead 56 of the tape 57 of the slide fastener 20.

When the slider 12' passes from the fastener 55 20 onto the guide 34 preparatory to passing onto the strip 10', the projections 52 of the tooth 51 will be forced into the recesses 54 on the teeth 53, straining the bead 56 on the end of the tape 57 so that the tooth 51 will be held by the teeth 60 53 with considerable force and resiliency, which may be controlled to overcome any normal tensioning which might occur at the bottom of the jacket.

If desired, instead of relying only upon the resiliency of the teeth 56 of the tape 57, resilient 65 spring means of either flat or coil construction may be included in the construction of Fig. 7 so as to assure a firmer grip of the tooth 51 between the teeth 53.

70 The slider 12', in passing back from the fastener 10' to the fastener 20 will exert a tensioning force sufficient to separate the teeth 51 and 53, which will be much greater than any tension normally occurring during wear or usage so that 75 no particular difficulty will be experienced in

opening the locked slide-off end of the hookless fastener 20.

At the point designated 50 in Fig. 6, the fastening device consists of a swinging latch member 51 which is pivotally connected at 59 to a 5 tongue 60 at the end of the bead 61 of the strip 11' of the slide fastener around the waist of the garment. The flattened end 62 of the guide 34 is provided with a pin 63, which is received in the recess 64 of the hook member 58. A spring 10 member, not shown, is associated with the pivot 59 to throw down the hook 58 to engage the pin 63 immediately the slider 12' has passed thereover.

Upon return of the slider 12' before the slider 15 moves or can be moved from the guide circular 34 onto the fastener strap 10' it is necessary to throw the latch 58 out so that it will pass through the upper channel 65 in Fig. 6 of the slider. Then the slider may be fitted upon the row of 20 teeth 10' and moved around the waist, as indicated by the arrows 28 and 29 in Fig. 5.

It will be noted that the guide straps are flattened, as indicated at 62 since the slider 12' must be taken off and placed on the slide fastener 20 25 and 10' with its axis coinciding with the axis of the fastener. For this reason the width of the guide 34 must decrease to approximately the dimension indicated at 66 on Fig. 6. It will be noted that the guide at its normal width has 30 about the same width as the length of the teeth 10', 36, 37, 51 and 53.

In operation, it is readily apparent that the wearer of the garment may open either the slide fastener 21 or both the slide fasteners 21 and 10' 35 during the normal working day. The fastener 21 may be opened without affecting the fasteners 10' and 20, and the slide fasteners 21 and 10' may be opened without affecting the fastener 20. In this manner a most convenient utilization may 40 be made of the garment throughout working hours.

It is obvious that the jacket 6' and the trousers 5' are interchangeable, are each singly replaceable and different jackets may be used with different trousers, or different trousers with different jackets.

In assuming the garment, the jacket carrying the slider 12' is first assumed. The slide fastener 20 may be connected together, as indicated at 50 32 and 33 in Fig. 6, and the slider cam 12' may then be run down to close the fastener 20.

As the slider 12' passes from the strip 20 it will lock the teeth 51 and 53 together, as indicated in Figs. 6 and 7.

Then the slider may be conveniently run around the guide 34 and the hook 42 may be engaged in the end of the guide 34, as indicated at 32 in Fig. 6.

The slider 12' is then conveniently run around 60 the waist to connect together the jacket 6' and the trousers 5' and as it passes beyond the slide fastener 10' the hook 58 will snap down to engage the pin 63 and lock the exit end of the slide fastener 10'.

Then the rows of teeth 36 and 37 may be engaged for operation of the slider 12', as indicated at 33 in Fig. 6, and the slider cam 12' may be run down to the position indicated in Fig. 5.

It will be noted that the combination garment 70 construction of the present invention enables the wearer thereof to assemble and detach the sections thereof with great facility and when so assembled, the garment produces a very neat appearance.

In using the construction of the present invention in overall garments, the many difficulties of one-piece overall garments have been avoided, particularly the disadvantage of getting into or 5 out of these garments because of the fact that they were difficult to engage or disengage with and from the shoulders of the wearer.

With other one-piece overall constructions, it 10 was necessary to lengthen the body of the garment to make it possible to don and remove the garment and the lengthening had to be carried out to such an extent that when the garment was worn it presented an ill-fitting appearance. Furthermore, the additional material required to 15 secure the additional length greatly increased the cost of production.

In old style one-piece garments, the trousers 20 were usually worn out before the jacket or shirt portions, and it was usually necessary to make a premature replacement of the entire garment, which is not necessary in the case of the present invention.

The overall construction shown in the application 25 is much superior to other constructions, in which either snap fasteners or buttons may be utilized for making connection between the jacket and trousers sections of the garment. With snap fasteners or buttons, it is evident that not only will considerable time be lost in securing the fastening means together, but in addition such fastening means will not be adequate to hold the garments together when strain is applied thereto, such as is occasioned when bending over.

The snap fasteners become detached from each 30 other and very often the buttons will be torn loose, or the buttonholes enlarged to such an extent that they will no longer retain the buttons.

It is obvious that the novel hookless fastener arrangements of the present invention, although 35 particularly applicable to overall constructions, and to one-piece combination children's garments, are also broadly applicable to enclosures, coverings and various articles of clothing in which it is desired to close different portions of the garment with hookless fastening devices with a single slider element even though such portions are at considerable angles to each other.

The present invention also illustrates a most novel method of locking both ends of a slide 40 fastener device, when the slider is altogether removed therefrom and it also indicates how a separable slide fastener may be initially engaged to enable the movement of a slider thereover, which novel features are of general application.

The garments prepared according to the present 45 application are found particularly suitable for laundering since the soap which catches in between the teeth during the laundering operation enhances the lubricating properties of the slide fastener and assures that it will slip through the teeth to cause engagement or disengagement of such teeth in a much more satisfactory manner.

It is also to be understood, of course, that separate slide fasteners may be employed for the 50 front of the jacket between the jacket and trousers and along the fly of the trousers.

What is claimed is:

1. An overall construction comprising separable 55 trousers and jacket sections, the jacket sections being provided with an open front and the trousers section being provided with an open fly, slide fasteners connected to the front of the jacket, to the fly of the trousers and to the adjacent upper edge of the trousers and lower edge of the jacket, and extending around the waist of said jacket and

trousers sections, said slide fasteners each consisting of a fabric strip to be sewn to the edges of the jacket and trousers section to be connected together or to each other, each of said strips being provided with a fabric bead and each of said beads being provided with and carrying a plurality of interengaging teeth, each tooth having opposite projections and recesses to engage with the opposite teeth of the same shape on the other strip, said strips or fasteners being entirely separable from each other, the slide fasteners along the front of the jacket and around the waist of the jacket and trousers sections being entirely separable and a cam slider element to cause engagement and disengagement of the slide fasteners for 15 engagement, means at the beginning of each of said slide fasteners to enable initial engagement of the slider therewith, locking means at the ends of the slide fastener of the jacket and slide fastener around the waist to lock said slide fasteners 20 when the slider is removed therefrom, and guide means between the slide fasteners on the front of the jacket and around the waist and also between the slide fasteners around the waist and along the front of the fly, whereby the slide fastener 25 may be drawn down to engage the slide fastener at the front of the jacket, then turned at 90° to connect the slide fastener between the jacket and trousers section and then turned another 90° to engage the slide fastener on the fly. 30

2. An overall construction comprising separable trousers and jacket sections, the jacket sections being provided with an open front and the trousers section being provided with an open fly, slide fasteners connected to the front of the jacket, to the fly of the trousers and to the adjacent upper edge of the trousers and lower edge of the jacket, and extending around the waist of said jacket and trousers sections, said slide fasteners each consisting of a fabric strip to be sewn to the edges 40 of the jacket and trousers section to be connected together or to each other, each of said strips being provided with a fabric bead and each of said beads being provided with and carrying a plurality of interengaging teeth, each tooth having an opposite projection and recesses to engage with the opposite teeth of the same shape on the other strip, said strips or fasteners being entirely separable from each other, the slide fasteners along the front of the jacket and around the waist of the jacket and trousers sections being entirely separable, a single cam slider element to cause engagement and disengagement of the slide fasteners said slide fasteners being connected by 45 guide means by which said single cam slide may be moved from one slide fastener to the other. 50

3. An overall construction comprising separable trousers and jacket sections, the jacket sections being provided with an open front and the trousers section being provided with an open fly, slide fasteners connected to the front of the jacket, to the fly of the trousers and to the adjacent upper edge of the trousers and lower edge of the jacket, and extending around the entire waist of said jacket and trousers sections, a single cam slider element to cause engagement and disengagement of the slide fasteners, means at the beginning of each of said slide fasteners to enable initial engagement of the slider therewith, and guide means between the slide fasteners on the front of the jacket and around the waist and also between the slide fastener around the waist and along the front of the fly, whereby the slide fastener may be drawn down to engage the slide fastener at the front of the jacket, then turned at 90° to connect 55 60 65 70 75 80 85 90 95

the slide fastener between the jacket and trousers section and then turned another 90° to engage the slide fastener on the fly.

4. In a garment of the type provided with a body covering portion and a pants portion, said pants portion and said body portion being detachably connected together and capable of being opened from each other and said body portion and said pants portion being provided with vertical openings along the front thereof; the combination therewith of slide fasteners on each of said openings, a single sliding cam member to be moved from one slide fastener to another and guide means devoid of teeth between said slide fasteners, said guide means consisting of a metal strip of substantially the same height as the teeth of the slide fastener to guide said slide means from one slide fastener to the other.

5. In a garment of the type provided with a body covering portion and a pants portion, said pants portion and said body portion being detachably connected together and capable of being opened from each other and said body portion and said pants portion being provided with vertical openings along the front thereof; the combination therewith of slide fasteners on each of said openings, a sliding cam member to be moved from one slide fastener to another and guide means devoid of teeth between said slide fasteners, said guide means consisting of a metal strip of substantially the same height as the teeth of the slide fastener to guide said slide means from one slide fastener to the other, one end of said strip being flattened to receive the cam member when drawn off a slide fastener.

6. In a garment of the type provided with a body covering portion and a pants portion, said pants portion and said body portion being detachably connected together and capable of being opened from each other and said body portion and said pants portion being provided with vertical openings along the front thereof; the combination therewith of entirely separable slide fastener means to close said openings, a sliding cam member and guide means devoid of teeth between said slide fasteners to enable engagement of said cam member with the initial end of said fastener, said guide means consisting of a metal strip of substantially the same height as the teeth of the slide fastener connected to the initial end of one side of the fastener, and a nose member with a hook to engage said guide means connected to the initial end of the other side of the fastener.

7. In a garment of the type provided with a body covering portion and a pants portion, said pants portion and said body portion being de-

tachably connected together and capable of being opened from each other and said body portion and said pants portion being provided with vertical openings along the front thereof; the combination therewith of an entirely separable slide fastening means on each of said openings, each means having a plurality of metallic fasteners permanently secured upon a pair of flexible tapes and a sliding cam device having a central channel and diverging channels extending from and communicating with said central channel, each means being provided with means for locking the initial end of the fastener characterized by a plate member secured to an end of one tape, including a metal strip having a hole and a hook having an abutment member secured to the end of the other tape to engage the other member.

8. In a garment of the type provided with a body covering portion and a pants portion, said pants portion and said body portion being detachably connected together and capable of being opened from each other and said body portion and said pants portion being provided with vertical openings along the front thereof; the combination therewith of a separable slide fastening means on each of said openings, each means having a plurality of metallic fasteners permanently secured upon a pair of flexible tapes and a sliding cam device having a central channel and diverging channels extending from and communicating with said central channel, means for locking the run-off end of the fastener means characterized by said device including a tooth having a double knob projection on one tape and two contacting teeth on the opposite tape with facing recesses to receive said double knob projection.

9. In a garment of the type provided with a body covering portion and a pants portion, said pants portion and said body portion being detachably connected together and capable of being opened from each other and said body portion and said pants portion being provided with vertical openings along the front thereof; the combination therewith of a separable slide fastening means on each of said openings, each means having a plurality of metallic fasteners permanently secured upon a pair of flexible tapes and a sliding cam device having a central channel and diverging channels extending from and communicating with said central channel, said fastener means also including means for locking the run-off end of the fastener characterized by a hook on the run-off end of one tape resiliently pressed toward the run-off end of the other tape and a pin on the other tape engaging said hook.
